Application September 6, 1939, Serial No. 293,586
 In Denmark October 19, 1938

2 Claims. (Cl. 200—55)

The present invention relates to an improved permutation lock, and one object of the invention is to provide a permutation which may be employed in connection with such door locks that have a bolt operated by means of a handle or knob attached to a spindle that is rotated by the said handle or knob, without any other alteration of the lock device than the removal of the said spindle and handle. Another object of the invention is to provide a construction of such a permutation device in which an axial and a rotational motion are required for the operation of the lock, said axial motion being utilized for operating a contact device in case of an incorrect adjustment of the permutation device. The invention is mainly characterized by a system of coaxially disposed rotatable shaft members each carrying on one end a knob provided with numerals or the like for determining the relative positions of the shafts that have means for preventing their displacement axially in relation to each other, but which allows the free rotational motion of the shafts independently of each other. The exterior shaft has means for connecting it to the lock bolt operating member of the lock when the system of shafts are displaced axially after the correct adjustment of the shafts, while means are provided for causing the displacement of contact operating means for a contact device, when endeavours are made to displace the system of shafts axially after an incorrect adjustment of the shafts.

One manner of constructing a permutation lock according to the invention is illustrated in the accompanying drawing, in which:

Fig. 1 shows the combined permutation lock in top elevation and partly in section,

Fig. 2 is a sectional view on line II—II in Fig. 1,

Fig. 3 a sectional view on line III—III in Fig. 1,

Fig. 4 a diagrammatic view of a detail in section and

Figs. 5 and 6 a modified manner of construction of a detail, seen in top and side elevation respectively, in Fig. 5 partly in section.

The members of a permutation lock according to the present invention are assembled between two end plates 1 and 2, that serve partly as guide plates for a movable part of the device comprising two rods 3 and 4 that are rigidly interconnected and spaced parallel to each other by means of split rings 5 and stays 6, and partly as assembly plates for circular discs 7 that are clamped between spacing tubes 9 arranged on clamping rods 8. The rods 3 and 4 are displaceable longitudinally in relation to the end plates, and each rod

carries a lug 10 that coacts with a contact device 11.

In Fig. 1 the device is shown in its inactive position, in which position it is held by means of coil springs arranged on the rods 3 and 4 between the end plate 1 and the nearest stay 6. In this position the lugs 10 are out of engagement with the contact devices 11. The end plates 1 and 2 have bearings for a system of shafts comprising a spindle 13 and axially arranged therewith two tubular shafts 14 and 15. These shafts and the spindle are displaceable longitudinally as a unit, and means are provided for preventing their relative displacement longitudinally, but which allow them to rotate independently of each other. Such means are shown diagrammatically in Fig. 4, where a shaft 28 corresponding to either the shaft 14 or spindle 13 is provided with a lug 29 engaging an annular groove formed in the inner wall of a tubular shaft corresponding to either the shaft 15 or 14.

The spindle 13 and each shaft 14 and 15 carries a radially extending pin 16 that has a length and a thickness corresponding to the width and length of the split in the rings 5 and the slots in the discs 7. The exterior tubular shaft 15 carries furthermore a toothed wheel 17, which upon the axial displacement of the system of shafts engages the teeth of an interiorly toothed tubular sleeve member 18, provided with a pin 19, that is attached to the bolt of a door lock 21 of conventional construction, and from which lock the handles and handle spindle have previously been removed. By means of the pin 19 it is possible to manipulate the bolt of the door lock 21 from the inner side of the door independently of the other members of the lock device according to the invention. The spindle 13 and shafts 14 and 15 extend to the outer side of the door 20, where each is provided with a knob 23, 24 and 25 respectively, by means of which they may be rotated independently of each other, and be displaced longitudinally as a unit. A numeral plate 22 on the outer side of the door in combination with marks on the separate knobs allows for an adjustment from the outside of the door of the members 13, 14 and 15 in relation to each other without actuating the rings 5, and to allow the axial displacement of the system of shafts for coupling the device to the sleeve 18 and thus to the bolt of the lock 21.

The combined permutation and alarm lock operates in the following manner. Upon rotating the knobs 23, 24 and 25 in accordance with the predetermined code for opening the lock, each

pin 16 is moved to register with the split in the adjacent ring 5 and the slit in the adjacent disc 7. The system of shafts is then displaced for procuring engagement between the toothed wheel 17 and the sleeve 18, and by turning the knob 23 the door lock 21 can be opened. If endeavours are made to extract the system of shafts before the correct adjustment of the knobs is made, the pins 16 will engage the upper edge of the rings 5, and thus displace the contact device 3, 4, 10, 11 for closing an electric circuit.

In Figs. 5 and 6 there is shown a modified manner of constructing the rings 5. In this instance the ring is formed as a projecting flange on a circular disc 26, the flange as well as the disc having a slot through which the pin 16 can pass. The disc 26 is by means of a folded edge attached to the rods 3 and 4 and clamped thereto by means of hook members 27 that are threaded for a nut, so that they are adjustable.

The details of construction of the above described device may be altered without deviating from the scope of the invention, the essential being that the rings are attached in such a manner that their position may be altered when desired.

I declare that what I claim is:

1. In a permutation lock, the combination of a plurality of coaxially disposed and independently rotatable but not axially displaceable shaft members, a flat and longitudinally slotted ring member arranged slidable on each shaft, rods arranged longitudinally displaceable parallel to the axis of the said shafts, means for attaching the ring members to the said rods, a radially extending pin attached to the one end of each shaft member adjacent the ring on the shaft, permutation means attached to the other end of each shaft member for adjustment of the pins in relation to the slotted portion of the rings, and a contact lug on the said rods disposed to actuate a switch device upon displacement longitudinally of the rods when any of the pins does not register with the slotted portion of the adjacent ring.

2. In a permutation lock as claimed in the preceding claim, the combination with the slotted ring member of a circular disc, a folded edge formed along the periphery of the said disc, and hook members transversely adjustable on the displaceable rods engaging detachably with their hooked end and the said folded edge of the disc.

EINER EIBY ANDERSEN HINNERFELDT.
